F/G. 5

FIG. 6

FIG. 1 is an isometric view of an article addressing machine showing our new design;

FIG. 2 is a front view thereof;

FIG. 3 is a reduced top plan view thereof;

FIG. 4 is a right side view thereof;

FIG. 5 is a left side view; and

FIG. 6 is a rear view thereof.

We claim:

The ornamental design for an article addressing machine, as shown.
